CLAIM

An ornamental design for a combined satellite dish and rotator, as shown.

DESCRIPTION

FIG. 1 is a perspective view of the satellite portion of the combined satellite dish and rotator, showing my new design; FIG. 2 is a right side elevational view thereof; FIG. 3 is a left side elevational view thereof; FIG. 4 is a front elevational view thereof; FIG. 5 is a rear elevational view thereof; FIG. 6 is a top plan view thereof; FIG. 7 is a bottom plan view thereof; FIG. 8 is a right side elevational view thereof in the collapsed position; and, FIG. 9 is a bottom view of the rotator portion of the combined satellite dish and rotator.

The broken lines in FIGS. 1 and 9 are for illustrative purposes only, and form no part of the claimed design. The surfaces of the combined satellite dish and rotator that are not shown form no part of the claimed design.
